UNITED STATES PATENT OFFICE.

CHARLES T. DOUGHERTY, DECEASED, LATE OF HUNTINGTON BEACH, CALIFORNIA, BY
WINFIELD W. SMITH, ADMINISTRATOR, OF COALINGA, CALIFORNIA, ASSIGNOR, BY
DIRECT AND MESNE ASSIGNMENTS, TO REVOLUTIONARY OIL WELL TOOL COMPANY.

OIL-WELL-TOOL OPERATOR.

Application filed April 22, 1926. Serial No. 103,682.

This invention relates to a tool for use in oil well drilling operations and especially to improvements in the construction of the tool described in the inventor's copending 5 application entitled "Oil well tool operator" filed December 3, 1923, Serial No. 678,371.

In the drilling of oil wells it is well known that numerous difficulties are encountered, such as parting of the casing, stripping of threads, freezing up of the casing, loss of tools, leaking joints, etc. Numerous tools have been devised for special uses, for instance, for fishing out lost tools, casing sections, etc., but they are not always dependable and often fail the purpose or particular operation for which they are designed, and at best necessitate a large supply of numerous costly tools, each of which requires practice to operate.

20 The object of the present invention is to generally improve and simplify the construction and operation of tools of the character described and particularly to provide a tool which is capable of handling problems encountered in oil well drilling operations, and which is also adapted to be attached to specialized tools for the purpose of more efficiently handling or operating the same.

25 The construction of the improved form of tool is disclosed in the accompanying drawings, in which:

30 Fig. 1 is a section of the bottom portion of an oil well which is being drilled by means of a rotary bit. The tool is also shown in section in this view and is inserted for the purpose of removing the rotary bit.

35 Fig. 2 is a view similar to Fig. 1 showing the tool in side elevation.

40 Fig. 3 is a continuation view of the upper end of Fig. 2 showing a drill line, a combination socket, a set of jars, etc. for operating the tool.

45 Fig. 4 is an enlarged cross section of one of the ratchet blocks taken on line 4—4 of Fig. 1.

Fig. 5 is an enlarged vertical section of the same ratchet block taken on line 5—5 of Fig. 4.

50 Fig. 6 is an enlarged detail view showing one of the pawls 8 and the block B in which the pawl is mounted.

Referring to the drawings in detail and particularly to Figs. 1, 2, 4 and 5, it will be noted that the tool proper consists of two

ratchet blocks generally indicated at A and 55 B. These blocks are maintained in spaced relation by means of a spacing tube 2 and they are provided with a tool holder 3 on the lower end which is carried by means of a tube 4.

Extending through the upper ratchet block is a helically twisted shaft 5 and forming a part of said shaft and extending downwardly therefrom through the ratchet block B is a square shaft 6 which is employed for the purpose of imparting a rotary movement to the tube 4 and the tool 3 carried thereby. The ratchet blocks work in opposition to each other to this extent; that, when the helically twisted shaft 5 is 65 lowered with relation to the ratchet block A, it will be locked against rotation so as to transmit a turning movement to the helically twisted shaft and the extension shaft 6. In that instance, the ratchet block B will 70 rotate. Vice versa it is possible to release the ratchet block A during downward movement of the helically twisted shaft and to lock the lower ratchet block against rotation.

75 In order to clearly explain these operations and the reasons therefor, the detailed construction of each ratchet block will be given. The upper ratchet block A is preferably constructed of steel. Its outer periphery is provided with a series of pockets 7 in which are mounted reversible pawls 8. These pawls engage the interior surface of the well casing when the ratchet block is rotated in one direction, thus freeing the pawls and permitting the ratchet block to rotate, but if the pawls are reversed and the ratchet block is rotated in the same direction the pawls will bite into the inner surface of the well casing and the ratchet 80 block will be locked against rotation.

85 By referring to Fig. 4, it will be noted that the pockets 7 are flared so as to permit the pawls 8 to be swung to one side or another as this is necessary to permit reversal of the same. Each pawl is provided with a slightly concaved outer face as indicated at 8^a to produce two biting edges 8^b and 8^c; the edge 8^b locking the ratchet block against 90 rotation in one direction and the edge 8^c 95 against rotation in the opposite direction. It will be noted that springs 7^a engage opposite sides of the pawls and that the tendency 100

105

will be to hold the pawls in a central position when the tool is removed from the well casing. It is accordingly only necessary to swing the pawls in the intended direction 5 when the tool is lowered into the casing as the interior diameter or clearance within the casing is such that the pawls cannot swing over center when in the casing. The pawls are held against endwise removal by a plate 10 9 and bolts 10.

The lower ratchet block is also preferably constructed of steel and it is provided with pockets for the reception of reversible pawls, such as indicated at 8^a, these pawls being 15 secured against endwise removal by a swivel joint cover 11 (see Fig. 5) which in turn is secured by means of bolts 12. The ratchet block B is permitted to freely rotate when the pawls are reversed. They, however, always assume a position opposite to the pawls 20 in the upper ratchet block, as one ratchet block is held while the other rotates, and vice versa. The center portion of the lower ratchet block is provided with a square shaped opening in which shaft 6 reciprocates as the helically twisted shaft is raised 25 and lowered, as will hereinafter be described.

The tool shown may be employed for numerous uses when drilling oil wells, but it 30 is particularly illustrated in the present instance as a device for removing or inserting a rotary bit such as indicated at C. The removal type of bit shown forms the subject matter of a copending application entitled "Detachable rotary bit" filed March 3, 1926, Serial No. 91,901. The bit consists of two blades 14 and 15 pivotally supported as at 16 in a holding nut 17 which is secured in a shoe 18 on the lower end of the well 40 casing by a threaded connection such as shown at 19. The problem of inserting the detachable rotary bit is therefore one of lowering the holding nut 17, together with the bits down into the well and then screwing 45 it into the shoe 18, and finally releasing the tool or device which lowered it into the well and screwing it into the shoe.

To clearly describe the operation of the tool, it will be supposed that the bit has 50 been in operation for a considerable time and has become so dull that it is desired to remove it and replace it with a resharpened bit. To accomplish this the tool proper is attached to a string of tools generally indicated at D and a drill line 20, and it is then lowered into the well. As it reaches the bottom, or in other words, the holding nut 17 and the shoe 18, the tool 3 will engage the upper end of the holding nut. The tool 60 3 is secured on the lower end of the tube 4 and it is provided with a tapered threaded projection 21. The upper end of the holding nut is similarly internally threaded. When engagement is made between the threaded 65 extension 21 of the tool 3 and the upper end

of the holding nut, the drill line and string of tools D are slowly lowered. The pawls in the upper ratchet block are set so that it is locked against rotation in a left-hand direction and the pawls in the lower ratchet block so that they will lock the lower ratchet block against rotation in a right-hand direction. 70

Thus, as the string of tools carried by the drill line is lowered, the helically twisted 75 shaft is also lowered and a turning movement is imparted thereto due to the fact that it passes through the upper ratchet block which is held stationary. The lower ratchet block is free to turn in a left-hand direction 80 and it will turn in this direction as the helical shaft turns in that direction and so does the shaft 6. Thus, turning movement is transmitted to the lower ratchet block through the shaft 6 as it passes through 85 a square shaped opening in the lower ratchet block, and as the tube 4 is secured to the lower ratchet block and the tool 3 is secured to the lower end of the tube, it is obvious that tool 3 will turn to the left and the threaded extension 21 will screw 90 into the upper end of the holding nut.

One or two revolutions are imparted during the lowering movement of the helically twisted shaft and as a considerable number of revolutions are required to screw the tool 3 down into the holding nut, it is obvious that a reciprocal movement must be imparted to the helically twisted shaft. This is accomplished by pulling up on the drill line and the string of tools D to which the oil well tool is attached. During upward movement the lower ratchet block grips and holds the tool 3 against rotation. The upper ratchet block, however, rotates freely and as this is the case, no rotary movement will be transmitted to the helically twisted shaft. The drill line in the string of tools D together with a helically twisted shaft 5 is raised and lowered a number of times. During each lowering movement, tool 3 is screwed further into the upper end of the holding nut 17 and it finally bottoms or sets therein. When this occurs further revolutions of the tool 3 will cause the holding nut 115 to unscrew with relation to the shoe 18, as a left-hand turn is employed. When the holding nut is completely unscrewed with relation to the shoe 18, it is only necessary to pull up on the drill line and to raise the oil well tool and the bit attached thereto to the surface where it may be removed and a resharpened bit placed in position on the tool 3. The whole string of tools is again lowered into the well until the threaded end of the holding nut 17 engages with the threads in the bottom of the shoe 18. In this instance, the pawls are reversed in the respective ratchet blocks, as it is now desired to 120 secure the upper block against turning 125 130

movement in the right-hand direction and the lower block against turning movement in the left-hand direction. It is necessary to impart a reverse turning movement to the tool 3 in order that the holding nut may be 5 screwed into the shoe.

Thus, after engagement has been made between the threads on the holding nut and the shoe, further downward movement causes the lower ratchet block to grip and the upper ratchet block to rotate. In other words, the helically twisted shaft is lowered without imparting rotary movement to the tool 3, but when the drill line and spring of 10 tools attached thereto is raised, the upper ratchet block grips and the lower ratchet block releases, thus causing the tool 3 to turn to the left and to thereby turn or screw the holding nut into the shoe. This operation 15 of raising and lowering the helically twisted shaft is repeated until the holding nut reaches its seat in the shoe. Further movement will cause the tool 3 to unscrew, as it is right-hand threaded and it thus 20 finally releases itself with relation to the holding nut and permits the whole string of 25 tools to be removed.

The oil well tool operator has numerous other uses:

30 (1) It may be employed to remove a frozen or lost casing section by section;

(2) To take out broken pieces of casing;

(3) To set up leaky joints at any point 35 desirable;

(4) To set up die collars or die nipples;

(5) To disconnect the casing in case of water leaks;

(6) To remove tools that are bull-dogged in the casing;

40 (7) To unscrew casing that is too rotten or corroded to stand strain from top of the hole;

(8) To tighten joints at any place desired without tonging the casing or spoiling joints 45 in the string above;

(9) To connect tool joints on lost tools or to unscrew the same.

(10) The tool may also be employed for 50 the purpose of rotating under-reamers of various makes and construction.

(11) The tool may be employed for the purpose of supporting a milling or cutting tool, whereby obstructions in the casing or on tools lodged in the casing may be cut 55 away.

All these operations are made possible due to the fact that specialized tools may be attached to this tool and may be rotated or 60 operated thereby, and also due to the fact that the tool may grip different sections of casings and unscrew them with relation to each other. The tool has other uses, for instance, such as obtaining and removing core samples. If casing sections are to be screwed 65 or unscrewed with relation to each other

tube 4 and the tool 3 may be eliminated if desired, as the ratchet blocks A and B serve the function of tightening up or unscrewing casing sections, but if the tool is to be employed for the purpose of removing a rotary 70 drill bit such as illustrated in the present instance, it is obvious that the tube 4 and the tool 3 may be required, and it should also be obvious that other tools may be attached to the tube 4 or to the threaded projection 75 of the tool 3 as desired.

Having thus described the invention what is claimed and desired to secure by Letters Patent is—

1. A tool of the character described comprising an upper and a lower ratchet block, a plurality of pawls on each ratchet block engageable with the interior wall of a well casing to secure the ratchet blocks against rotation in one direction, a nut in the upper 80 ratchet block, a helically twisted shaft extending through the nut and slidably therein, an extension shaft on the lower end of the helical shaft extending through the lower ratchet block and adapted to transmit a 85 turning movement thereto and a tool holder carried by the lower ratchet block and turnable therewith.

2. A tool of the character described comprising an upper and a lower ratchet block, 95 a plurality of pawls on each ratchet block engageable with the interior wall of a well casing to secure the ratchet blocks against rotation in one direction, a nut in the upper ratchet block, a helically twisted shaft extending through the nut and slidably therein, an extension shaft on the lower end of the helical shaft extending through the lower ratchet block and adapted to transmit a turning movement thereto, a tube secured to the 100 lower ratchet block and rotatable therewith and a tool holder carried by said tube.

3. A tool of the character described comprising an upper and a lower ratchet block, 110 a plurality of pawls on each ratchet block engageable with the interior wall of a well casing to secure the ratchet blocks against rotation in one direction, a nut in the upper ratchet block, a helically twisted shaft extending through the nut and slidably therein, an extension shaft on the lower end of the helical shaft extending through the lower ratchet block and adapted to transmit a 115 turning movement thereto, and means whereby a predetermined spacing is maintained 120 between the ratchet blocks.

4. A tool of the character described comprising an upper and a lower ratchet block, 125 a plurality of pawls on each ratchet block engageable with the interior wall of a well casing to secure the ratchet blocks against rotation in one direction, a nut in the upper ratchet block, a helically twisted shaft extending through the nut and slidably therein, an extension shaft on the lower end of the 130

helical shaft extending through the lower ratchet block and adapted to transmit a turning movement thereto, a spacing tube connecting the ratchet blocks and a swivel connection between each ratchet block and said tube.

5. A tool of the character described comprising an upper and a lower ratchet block, a plurality of reversible pawls in each ratchet block engageable with the interior wall of a

10 well casing to secure the ratchet blocks against rotation in either direction, a nut in

the upper ratchet block, a helically twisted shaft extending through the nut and slidably therein, and a second shaft forming an extension of the twisted shaft and secured thereto, said extension shaft being square in cross-section and extending through the lower ratchet block to transmit the rotary movement thereto.

15 WINFIELD W. SMITH,
Administrator of Charles T. Dougherty, Deceased.
